Inventor

Joseph E. Ring

UNITED STATES PATENT OFFICE.

JOSEPH E. RING, OF ALBANY, NEW YORK.

TOBACCO PIPE.

Application filed March 8, 1924. Serial No. 697,761.

To all whom it may concern:

Be it known that I, JOSEPH E. RING, a citizen of the United States, residing at Albany, in the county of Albany and State of New York, have invented certain new and useful Improvements in a Tobacco Pipe, of which the following is a specification.

This invention relates to smoking appliances, and more particularly to attachments 10 for the stems of pipes and the like.

An important object of the invention is the provision of means in a pipe stem or the like to prevent passage of moisture to the mouth of the smoker.

15 A further object of the invention is the provision of a pipe which will prevent the passage of particles of tobacco or the like through the pipe stem.

A still further object of the invention is 20 to provide a device of this character which is comparatively simple, yet durable of construction and will greatly improve the smoking action of the pipe.

Other objects and advantages of this 25 invention will be apparent during the course of the following description.

In the accompanying drawing forming a 30 part of this specification and in which like numerals are employed to designate like parts through the same:

Figure 1 is a longitudinal sectional view of a pipe embodying my invention,

Figure 2 is a similar view showing the 35 detailed construction also in section,

Figure 3 is an enlarged transverse sectional view taken on the line 3—3 of Figure 2, and

Figure 4 is a similar view taken on the 40 line 4—4 of Figure 2.

In the drawing, wherein for the purpose 45 of illustration is shown the preferred embodiment of my invention, the numeral 5 indicates the tobacco bowl which has a tubular shank 6 formed thereon and forming

50 part of the pipe stem. The tubular shank 6 has a longitudinal bore 7 formed therein, the extremity adjoining the bowl 5 tapering to a comparatively small port 8. Firmly fitted into the tubular shank 6 is a mouth-piece or bit 9 which is provided with a longitudinal bore comparatively small in diameter denoted by the numeral 10, the in-

ner extremity thereof expanding to the size of the bore 7 formed in the tubular shank 6.

55 My invention particularly comprises a cylindrical container 12 which is constructed of thin metal or other desirable material, one extremity being reduced and forming a cylindrical extension 13 which is adapted to engage a cylindrical screen member 14 which 60 is comparatively small in cross section, the other extremity of the screen abutting the small bore 10. The other extremity of the cylindrical container 12 is provided with a similar extension 15 which extends through 65 the port 8 and connects with the inside of the bowl 5. The container 12 has a flat screen 16 positioned on the interior thereof and adapted to snugly fit the inner contour. The forward screen member 14 is covered by 70 a felt wrapper 17 which fills the front extremity of the longitudinal bore and absorbs the moisture as it passes through the screen.

It is obvious that the bit 9 and bowl member 75 will be held in position by the cylindrical container 12 which snugly fits the bores formed in the bit and shank.

In use, the device may be readily inserted 80 within the shank of the pipe and obviously prevents the passage of tobacco or other particles or the moisture which may accumulate in the bottom of the bowl thereby enabling the smoker to draw clean and dry smoke through the mouth piece. It is also contemplated to so construct the device as to 85 make it applicable to many styles of pipes now on the market, the insertion thereof greatly benefiting the smoker.

It is to be understood that the form of my 90 invention herewith shown and described is to be taken as the preferred example of the same, and that various changes as to the shape, size and arrangement of parts may be resorted to without departing from the spirit of the invention, or the scope of the subjoined claim.

Having thus described my invention, I 95 claim:

A tobacco pipe having a bowl portion and a stem portion, the stem portion having a 100 bore of relatively large diameter which is connected with the interior of the bowl by a bore of relatively small diameter passing through the bottom wall of the bowl, a cy-

lindrical container fitting snugly in the bore of the stem and having diametrically reduced end extensions, one of which fits snugly in the bore in the bottom wall of the bowl and a cylindrical screen pinning over the other end extension of the container and disposed longitudinally of the stem and having

10
In testimony whereof, I have affixed my signature.

JOSEPH E. RING.
